REFRIGERATOR

Robert H. Tull, Springfield, Mass., assignor to Westinghouse Electric & Manufacturing Company, East Pittsburgh, Pa., a corporation of Pennsylvania

Application July 20, 1938, Serial No. 220,207

5 Claims. (Cl. 62—102)

This invention relates to refrigerators, and particularly to refrigerators of the type wherein the air in the refrigerated storage chamber is forcibly circulated therein.

One object of the invention is to provide a refrigerator of the forced convection type in which the refrigerated storage chamber is maintained at a high humidity.

Another object is to provide a refrigerator in which the air circulation is uniform in all parts of the storage chamber.

Another object is to apportion and arrange the various elements of the refrigerator to make a large portion of the refrigerated chamber available for food storage.

These and other objects are effected by my invention as will be apparent from the following description and claims taken in connection with the accompanying drawings forming a part of this application, which show a reach-in cooler. The invention, however, is not limited to this specific embodiment, as it is applicable to numerous other types of refrigerated chambers.

In the drawings, Fig. 1 is a vertical section through the cabinet on the line I—I of Fig. 2;

Fig. 2 is a vertical section through the cabinet on the line II—II of Fig. 1.

Referring now to the drawings, numeral 10 designates a cabinet of conventional construction which comprises an outer shell 11 and a horizontal partition 12 therein. The partition 12 divides the cabinet 10 into an upper refrigerated food storage chamber 13 and a lower machine compartment 14. The bottom edges 15 of the shell 11 are turned inwardly and blocks 16 are secured to their lower surfaces to form feet on which the cabinet 10 rests.

On the upper surface of the turned edges 15 is a platform 17 upon which is secured a refrigerant liquefying unit 18 of the well-known compressor-condenser type. The remaining portion of the lower compartment 14 is partitioned off to provide a dry storage space 19, access to which may be had by means of a door 21 forming the closure for an opening in the front wall of this storage space.

The food storage chamber 13 comprises an inner shell 24 and heat insulating material 23 between the adjacent portions of the shell 11 and the partition 12. An opening 26 in the front wall 27 and a hinged door 28 therein provide for access to the chamber 13. Also in the chamber 13 are shelves 29 for supporting the articles of food to be refrigerated.

5 A cooling unit or evaporator 31 is located in the top of the storage chamber 13 which unit is of a size substantially equal to the horizontal cross-sectional area of the chamber. The unit 31 is secured in the food storage chamber in a slightly inclined position so that a tapered air space remains above the cooling unit 31. The cooling unit 31 comprises a series of parallel and spaced-apart fins 32 through which a tube 33 passes back and forth in a single layer. The tube communicates through ducts 34 and 35 with the refrigerant liquefying unit 18.

10 Below and parallel to the cooling unit 31 is a series of Z-shaped channels 36, which channels overlap but are spaced from one another to permit the passage of air therebetween. These channels 36 catch the water which condenses and drips from the cooling unit 31 and conduct this water to a trough 37 from which it drains through 15 a tube 38 passing through the refrigerated chamber 13 into a pan 39 located in the bottom thereof. A drain pipe 41 connects with the pan 39 but has its entrance opening 42 located somewhat above the bottom of the pan 39 so that 20 the latter retains a small amount of water 40 to humidify the air in the refrigerated chamber 13.

25 The edges of the pan 39 are turned inwardly and upon them rests a foraminated plate forming a false bottom 43 in the refrigerated chamber 13. The false bottom 43 is supported above the surface of the water 40 in the pan 39 to provide a space 44 through which air may be circulated.

30 35 Connected with this space 44 is an inlet conduit 45 of a blower element comprising a casing 46, a fan 47, and a motor 48 for driving the fan 47. The fan 47 draws the air from the space 44 and passes it through a vertical duct 49 located 40 in the refrigerated compartment 25, through a divergent adapter 51 to the larger end of the tapered air space above the cooling unit 31. From here the air flows through the cooling unit 31, through the spaces between the Z-shaped 45 channels 36, through the refrigerated chamber 28, through the foraminations in the false bottom 43, and over the water 40 in the pan 39 where it is humidified and then recirculated by 50 the fan 47.

55 The fins 32 of the cooling unit 31 are at right angles to the general flow of the air in the tapered air space and deflect the air downwardly in the shortest path through the cooling unit 31. The air is thus in contact with the cooling

unit 31 for only a short period of time and is consequently cooled through only a few degrees of temperature on each passage through the cooling unit 31. This cooling is substantially just sufficient to abstract the heat absorbed by the air on passing over the articles in the refrigerator and along its walls. This small degree of cooling results in but little moisture being abstracted by the cooling unit 31, and the humidity of the air in the chamber 25 will consequently be relatively high. Because of this high humidity, fruits, vegetables, meats, and similar moisture containing foods will retain their condition and their palatable appearance when stored in the refrigerator.

The large area of the cooling unit also permits of its being maintained at a higher temperature and at a correspondingly higher suction pressure so that the power consumption of the refrigerating apparatus is decreased.

The large air collecting area formed by the false bottom 43 of the refrigerated chamber 13 and the large air discharging area at the top of the refrigerated chamber 13 provides for uniformity of air flow and consequently also of temperature throughout this space.

From the above it will be apparent that this invention provides a high humidity refrigerator, the temperature of which will be uniform throughout the refrigerated chamber. It will also be apparent that a large portion of the refrigerated chamber is available for the storage of foods.

While I have shown my invention in but one form, it will be obvious to those skilled in the art that it is not so limited but is susceptible of various changes and modifications without departing from the spirit thereof, and I desire, therefore, that only such limitations shall be placed thereupon as are imposed by the prior art or as are specifically set forth in the appended claims.

What I claim is:

1. In a refrigerator, the combination of a chamber, a flat, substantially horizontal cooling unit therein and adjacent to but spaced from the top thereof, said cooling unit cooperating with the walls of said chamber to prevent passage of substantial quantities of air around the edges of the cooling unit, a multiplicity of closely-spaced transverse air passages substantially throughout the flat surface of the cooling unit, a duct communicating with the lower portion of the chamber and with the space between the cooling unit and the top of the chamber and means for forcibly propelling air upwardly through said duct, said air traveling downwardly and substantially uniformly through all of the air passages of the cooling unit.

2. In a refrigerator, the combination of a chamber, a flat, substantially horizontal cooling unit therein and adjacent to but spaced from the top thereof, said cooling unit extending substantially to the vertical walls of the chamber, a multiplicity of closely-spaced vertical air passages substantially throughout the flat surface of

the cooling unit, a duct communicating with the lower portion of the chamber and with the space between the top of the chamber and the cooling unit, said space being substantially devoid of any obstruction to the flow of air toward the cooling unit, and means for propelling air upwardly through said duct, the air thereafter traveling downwardly and substantially uniformly through the vertical air passages of the cooling unit.

3. In a refrigerator, the combination of a chamber, a flat, substantially horizontal cooling unit therein and adjacent to but spaced from the top thereof, said cooling unit cooperating with the walls of said chamber to prevent passage of substantial quantities of air around the edges of

the cooling unit, a multiplicity of closely-spaced substantially vertical air passages throughout the flat surface of the cooling unit, a duct communicating with a large area adjacent the bottom of said cabinet and with the space between the top of the chamber and the cooling unit, said space communicating directly with substantially all of the vertical air passages of the cooling unit, and means for propelling air through said duct, said air traveling through all of the air passages of the cooling unit substantially uniformly.

4. In a refrigerator, the combination of a chamber, a large, flat and substantially horizontal cooling unit therein and adjacent to but spaced from the top thereof, a multiplicity of closely-spaced vertical air passages substantially throughout the flat surface of the cooling unit, a drip collector below said cooling unit, said drip collector comprising spaced-apart troughs, a duct communicating with the lower portion of the chamber and with the space above the cooling unit and means for propelling air upwardly through said duct, the air thereafter traveling downwardly substantially uniformly through the vertical air passages in the cooling unit, said cooling unit cooperating with the walls of said cabinet and with said duct to prevent downward passage of said air around the edges of the cooling unit.

5. In a refrigerator, the combination of a chamber, a large, flat and substantially horizontal cooling unit therein adjacent to but spaced from the top of said chamber, a multiplicity of closely-spaced transverse air passages substantially throughout the flat surface of the cooling unit, a drip collector below said cooling unit, a water pan adjacent the bottom of said chamber, means for conducting the moisture from the drip collector to the water pan, a duct communicating with the lower portion of the chamber and with the space between the top of the chamber and the cooling unit and means for propelling air upwardly through said duct, said air thereafter traveling downwardly and uniformly through the air passages in the cooling unit, said cooling unit cooperating with the walls of said chamber and with the duct to prevent the passage of substantial quantities of air around the edges of the cooling unit.
